DOOR LATCH OF THE BORED-IN TYPE

Bert A. Quinn, St. Paul, Minn.

Application January 2, 1941, Serial No. 372,748

3 Claims. (Cl. 292—126)

My present invention relates to devices generally designated as "door latches" and is in the nature of an improvement on door latches of the type disclosed and claimed in my pending application Serial Number 299,115 filed October 12, 1939. In the application of door latches of the above noted type, it has been necessary to cut deep and quite large notches in the free edge of the door, thereby weakening and defacing the free edge of the door.

My present invention provides a simple and highly efficient way of applying these door latches to doors simply by boring a hole through the door away from the free edge of the door and without in any way defacing the free edge of the door. Otherwise and generally stated, this invention provides an improvement in locks of the above character adapting them to be applied to doors on the plan generally designated as the "bored-in" type. The advantages of bored-in type latches over the notched or cut-in type are that the free edges of the door are not notched or defaced and that the hole for the latch may be quickly and properly located and formed.

In my present improved lock, I accomplish the above results by the use of a latch casing or core that is capable of being inserted endwise into the hole formed therefor in the door and to be positioned and held and the hole covered by suitable escutcheon plates. There will be both inside and outside escutcheon plates and preferably, the latch casing or core is formed integral with or otherwise rigidly secured to the inside escutcheon plate.

A commercial form of the improved lock is illustrated in the accompanying drawings wherein like characters indicate like parts throughout the several views.

Referring to the drawings:

Fig. 1 is a view, chiefly in horizontal section but with some parts in full plan view, showing portions of a door frame and a door and with the latch mechanism applied to the latter;

Fig. 2 is a vertical section taken on the line 2—2 of Fig. 1, the parts of the door frame being removed;

Fig. 3 is a vertical section taken approximately on the line 3—3 of Fig. 1;

Fig. 4 is a section taken approximately on the line 4—4 of Fig. 1, parts being broken away;

Fig. 5 is a view in perspective showing the outside latch plate;

Fig. 6 is a view in perspective showing the inner escutcheon plate as formed integral with the latch casing;

Fig. 7 is a view corresponding to Fig. 1 illustrating the same structure except that the outside escutcheon plate is dished or offset to compensate for a thin door; and

Fig. 8 is a fragmentary view looking at the face of the dished latch plate and showing a portion of the door frame.

The door frame illustrated is indicated by the numeral 10 and the casing by the numeral 11.

10 This frame 10 is rabbeted in the customary way, and just inward of the rabbet is provided with a "bored-in" strike plate 13 set into a recess counter-bored into the frame 10. This strike plate is in the form of a thin sheet metal cup having a peripheral flange that overlaps the hole 14. The construction and operation of this cup-shaped strike plate will be hereinafter more fully described.

15 The door 15, which may be assumed to be a storm door or screen door hinged in the usual way, is provided near its free edge with a latch-receiving bored hole or aperture 16 that is spaced from the free edge of the door leaving the free edge of the door in perfect or unmarred formation.

20 The latch casing 17, which is adapted to be inserted or threaded endwise through the hole 16, is preferably a sheet metal structure bent into flattened tubular form. Fig. 6 illustrates the manner in which this latch casing 17 and the inside escutcheon plate 18 may be formed from a single piece of normally flat sheet metal. The escutcheon plate 18 thus formed is preferably applied to the inner side or face of the door where it will cover the inner end of the hole 16 and will hold the casing 17 properly positioned when the said escutcheon plate-forming portions 18 are secured to the door by devices such as

25 screws 19, best shown in Fig. 2. The outside escutcheon plate 20 will be independently secured to the door by screws or other suitable devices.

The handle 21 of the latch here illustrated is preferably a double-ended lever of substantially C-shape or outline and may be very much like that of my prior application, being preferably a sheet metal structure formed channel-shaped in cross section. This handle or lever 21 is provided with a pivoted latch dog 22 that is preferably placed within the channel of the handle 21

30 with its cam-acting latch lug 22' projecting through a slit in said handle so that it will be brought into proper registration with the latch plate 13 when the door is closed. The handle is 35 pivoted to the latch casing 17 and said latch dog

is pivoted to said handle by a common pivot pin or bolt 23.

The handle 21 and the latch dog 22 are both subject to a common coiled spring 24 that is pressed directly against the latch dog 22 and reacts against a stop 25 formed in the back of the casing 17. The spring 24 indirectly acts on the handle 21 by pressing the latch dog 22 against the same in a direction to hold the latch lug 22' engaged with the slot in the latch plate 13.

The manner in which the latch mechanism may be quickly applied is probably obvious, but may be briefly stated as follows:

The lever or handle 21 and the latch dog, already pivotally connected to the latch casing 17, will be applied by inserting one end of the handle through the hole 16 and pressing the latch casing 17 into the hole and then securing the inside escutcheon plate 18 to the door, as already described, and this, as is evident, positions the operative parts of the latch to the door. The outside escutcheon plate 28 can then be readily applied by slipping the same over the outer end of the handle and securing the same to the door.

The structure illustrated in Fig. 7 is the same structure as that illustrated in the other views, with the exception that the outside escutcheon plate 28a is recessed to receive a projecting portion of the latch casing when the latter is applied to a door 15a that is thinner than the door 15 shown in the other views.

As a means for locking the latch in latching position, shown in Figs. 1 and 7, an oscillatory lock piece 26 is shown as pivoted to the inside escutcheon plate 18. This lock piece is not, however, herein broadly claimed, but it may be stated that when in the position shown in Fig. 2, the latch mechanism will be free for operation, but that when the said latch piece is turned under the latch dog 22, the latter will be securely held in its latching position.

The construction and arrangement of the strike plate 13 is highly important. Its body portion is designed to fit rotatively within the recess 14 and it is secured to the frame 10 by a wood screw 27. The counterbore formed in the frame 10 for the reception of the strike plate 13 is preferably of the same diameter as the hole 16 so that the same bit may be used for both purposes. In the use of the boring tool for forming the recess 14, the lead point of the bit will start a hole for the screw 27 and which hole will be at the axis of the counterbore. The operative or latch-engaging interior of the strike plate 13 is eccentric to the axis of the screw 27 and to the axis of the exterior of said strike plate so that by rotary adjustments of the strike plate, its engagement with the latch lug 22' will always be such as to take up all slack between the door and the door frame and thus prevent rattling. In the arrangement of the strike plate shown, its interior, instead of being a true circle eccentric to the axis of screw 27, is formed with diametrically opposite latch-engaging surfaces 13a and 13b, the former of which is much closer to the

axis of the screw 27 than is the surface 13b. Of course, when screw 27 is tightened, the strike plate 13 will be secured in the particular adjustment in which it may be set to take up the slack. This improved rotatively adjustable strike plate is capable of use in connection with any form of latch or door lock that has a projecting hook or cam-acting element for engagement with such strike plate.

Another important feature should be noted, to wit: that the escutcheon plate 18, at that portion thereof that overlaps with the door frame 10, is inwardly offset at 18a and is of such size that it is pressed into the hole 16 with its exposed face flush with the inner face of the door 15. This feature is highly important because it makes it unnecessary to form a mortice, either in the door or in the door frame.

It is further highly important to note that both of the escutcheon plates terminate short of the free edge of the door. This is important because it permits the free edge of the door to be planed off to properly fit the door opening without removing or disturbing the lock mechanism.

While the improved latch has, in practice, been found especially serviceable for storm and screen doors, it is, of course, capable of being applied to various other kinds of doors.

In actual practice this improved device has been found to be highly efficient for the purposes had in view. In accordance with the statutes, I have illustrated and described a commercial form of the device, but it will be understood that the same is capable of various modifications as to details of construction and arrangement of parts within the scope of the invention herein disclosed and claimed.

What I claim is:

1. A lock mechanism comprising a tubular casing having opposite rounded side portions adapted to fit snugly within a cylindrical aperture in a door and intermediate flattened side portions, an anchoring escutcheon plate for one side of the door extending at right angles to and integral with adjacent ends of the flattened sides of the casing, a double-ended handle extending through the tubular casing and intermediately pivoted to the flattened sides thereof, said handle having a latch dog projecting therefrom at a point offset from the handle pivot, and a spring located within the casing and compressed between the handle and casing and exerting yielding force tending to render the latch dog operative.

2. The structure recited in claim 1, and a second escutcheon plate for the opposite side of the door recessed to receive the projecting end portion of the tubular casing.

3. The structure recited in claim 1, wherein the integral escutcheon plate comprises a right angularly flanged portion of each flattened side of the tubular casing, and means joining said flanged portions adjacent a rounded side of the casing.

BERT A. QUINN.
